UNITED STATES PATENT OFFICE.

PAULINE B. WARNER, OF ST. PAUL, MINNESOTA.

VIBRATING FIGURE TOY.

Application filed March 1, 1924. Serial No. 696,203.

To all whom it may concern:

Be it known that I, PAULINE B. WARNER, a citizen of the United States, residing at St. Paul, in the county of Ramsey and State 5 of Minnesota, have invented a new and useful Vibrating Figure Toy, of which the following is a specification.

My invention relates to improvements in toys, one object thereof being to provide a 10 simple, durable and inexpensive novelty with which children and particularly those of tender years may entertain themselves without danger of harm in play.

With the foregoing and other objects in 15 view, which will appear in the following description, the invention resides in the novel combination and arrangement of parts and in the details of construction hereinafter described and claimed.

20 In the drawings, Fig. 1 is a perspective view of a toy embodying my invention and Fig. 2 is a transverse sectional view of the same.

25 Referring to the drawings, wherein similar reference characters have been used in the two views to designate similar parts, it will be observed that the illustrated embodiment of my invention includes a base A, 30 vibrative forms B on said base and attaching means C for securing the base to a support.

The base A is a thin elongated block of 35 wood or other suitable material, the same being recessed as at 10 at the under side thereof and formed with a series of aligned 40 socket forming bores 11 therethrough.

The forms B each comprise a tubular stem 45 of rubber, the same having a bead or shoulder 13 at its lower end and an object, preferably in the form of a head 14, at the upper end thereof. A form B is supplied 50 for each bore 11 in the base A, the lower end of each stem 12 being snugly fitted in its respective bore 11 with the bead 13 caught beneath the bottom of the base A and within the recess 10 therein. These forms are 55 preferably molded structures, the heads 14 and beads 13 being integral with the stems 12. Being solid, the heads 14 lend sufficient 60 weight to the stems 12 to render them actively vibrative through relatively great limits. Said stems 12 are relatively spaced 65 to bring each head 14 within range of its adjacent head or heads, whereby the swaying 70 of one figure B will result in impact between

it and the next figure and so on through the remainder of the series in either direction. Thus, it will be understood that the toy provides a plurality of moving figures in which active movement may be set up through successive impacts between the heads initiated by imparting movement to one of said figures. The heads 14 are preferably molded with fanciful colored faces, which combined with the ready movement of the figures B 60 provide for inviting play and the entertainment of children. Since the figures B are formed of rubber, there is no danger of a child harming itself in playing with the 65 toy.

The attaching means C comprises a strap 70 threaded through slots 15 in the ends of the base A and provides for conveniently and detachably securing said base to a support such as the tray of a high-chair or other suitable anchorage.

Changes in the specific form of my invention, as herein disclosed, may be made within the scope of what is claimed without departing from the spirit of my invention.

Having described my invention, what I claim as new and desire to protect by Letters Patent is:

1. In a toy, a base, a series of stems of resilient rubber secured to said base, resilient rubber objects, one for each stem, each object being secured to its respective stem at the free end thereof and being sufficiently heavy to render said stem actively vibrative through relatively great limits, said stems 80 being relatively located to bring each object within range of adjacent objects, whereby a continuity of movement may be set up in the series through a succession of impacts initiated by one of said objects and passed 85 on to others through intermediate objects.

2. In a toy, a base, a series of resilient stems secured to said base, a plurality of objects, one for each stem, each object being secured to its respective stem at the free end 90 thereof and being sufficiently heavy to render said stem actively vibrative through relatively great limits, said stems being relatively located to bring each object within range of adjacent objects, whereby a continuity of movement may be set up in the series through a succession of impacts initiated by one of said objects and carried on 95 through the remaining objects.

3. In a toy, a base recessed at its under 100

side and formed with a bore therethrough, a hollow tubular stem of resilient rubber snugly fitted at one end in said bore, said stem having an annular bead thereon housed within said recess and serving as a shoulder to engage the under side of the base and secure the stem from withdrawal therefrom,

and an object on the stem lending sufficient weight thereto to render the same actively vibrative under initial flexing thereof.

In testimony whereof, I have signed my name to this specification.

PAULINE B. WARNER.
